UNITED STATES PATENT OFFICE.

PHILIP JACOB MEAHL, OF BAYONNE, NEW JERSEY, ASSIGNOR TO THE AEOLIAN COMPANY, OF NEW YORK, N. Y., A CORPORATION OF CONNECTICUT.

MUSIC-ROLL-MARKING MACHINE.

No. 837,317.

Specification of Letters Patent.

Patented Dec. 4, 1906.

Application filed January 23, 1906. Serial No. 297,424.

To all whom it may concern:

Be it known that I, PHILIP JACOB MEAHL, a citizen of the United States, and a resident of Bayonne, county of Hudson, and State of New Jersey, have invented certain new and useful Improvements in Music-Roll-Marking Machines, of which the following is a specification.

My invention relates to a device for printing upon a music-sheet one or more series of marks intended to guide the player in rendering the composition, although in a broader sense the machine is capable of printing on a sheet of any sort any desired marks or indicia.

In the case of the perforated music-sheets used for controlling and operating mechanical musical instruments and mechanical players for musical instruments it is important to mark thereon directions to the player for producing the various musical effects. In the form of the device illustrated I have shown means for marking on the sheet a broken series of indicia for the force with which the composition is to be rendered, as "PP," "P," "F," "A," and "D" or the like, and in addition a continuous irregular or zigzag line, which may be used in combination with an expression lever or device on the instrument for continuously controlling the expression.

Further objects of the invention will appear in the specification and will be pointed out in the claims.

In the drawings, Figure 1 is a front elevation, partially broken away, of a machine embodying my invention. Fig. 2 is a side elevation, partly in vertical section and with certain parts omitted, of the same machine. Fig. 3 is a partial top plan view of the same machine. Fig. 4 is an enlarged detail of a portion of the machine shown at the right of Fig. 1. Fig. 5 is a vertical section taken through the plane 5 5, Fig. 1. Figs. 6 and 7 are partial diagrammatic plan views of a master-sheet and a music-sheet, respectively. Fig. 8 is a partial plan view of the rear of the machine, showing a modification. Fig. 9 is a partial vertical section through the plane 9 9, Fig. 8. Fig. 10 is a vertical section through the plane 10 10, Fig. 9. Fig. 11 is a partial vertical section through the plane 11 11, Fig. 2, but showing the modified form of the device. Fig. 12 is a vertical section through

the plane 12 12, Fig. 11. Fig. 13 is a partial vertical section of a part of the device shown in Fig. 12 on a still further enlarged scale. Fig. 14 is a partial horizontal section through the plane 14 14, Fig. 9. Fig. 15 is a longitudinal vertical section through the plane 15 15, Fig. 8. Fig. 16 is a transverse vertical section through the plane 16 16, Fig. 8.

Referring to Figs. 1 to 7 of the drawings, 1 designates the frame of the machine, which carries in suitable bearings at its rear end a shaft 2, on which the sheets to be printed are wound. At the forward end of the machine is a pair of rolls 3 4, geared together for simultaneous movement in opposite directions. On the extended shaft 5 of the roll 4 is a clutch member 6 for engaging with a co-operating clutch member 7 on a shaft 8, which carries a roll 9, acting in co-operation with a second superposed roll 10, the two being geared together and suitably supported in a frame 11. On the frame 11 is also supported a tracker 12, having ducts 13, (see Fig. 5,) the rolls 9 and 10 and tracker 12 being intended to co-operate with the master-sheet 64, by which the action of the printing device is controlled. On the shaft 5 is a toothed wheel 14, engaging with a dog 15 on a rock-bar 16, which is connected by a link 17 with an eccentric 18 on a shaft 19, which may be the main driving-shaft of the machine. Mounted one on each side of the machine are shafts 20 and 21, carrying drums 22, 23, 22^X, and 23^X, each of which is flanged for the reception of a plurality of carbon-ribbons 66^X, the function of which will be explained hereinafter. The shaft 20 is provided with a toothed wheel 24, (see Fig. 2,) acted on by a dog 25 at the end of a bar 26, the upper end of which is acted on by a cam 27 on the link 17, whereby the shaft 20 is rotated step by step. The shaft 21 is shown as provided with a crank 28 for rewinding the carbon-ribbons thereon. Mounted near the rear of the frame 1 and directly above the path of the carbon-ribbons passing over the drums 22 23 is a vertical container 29, having lateral openings 30 at its lower end. A laterally-moving plunger 31, Fig. 4, is adapted to pass through the openings 30 in the lower end of the container 29 and has pivoted to it a rock-shaft 32, the upper end of which is connected by a link 33, Fig. 3, to a pneumatic 34, mounted

on the frame 1 and connected by a flexible tube 341 to one of the ducts 13 in the tracker 12. A spring 35 (shown in Fig. 4) acts to hold the plunger 31 normally out of operation. 5 Adjacent the container 29 is a vertical plunger 36, at the upper end 37 of which is pivoted a bar 38, which lies adjacent to the path of a cam 39 on the shaft 19, so that the plunger 36 may be depressed thereby. Interposed, 10 however, between the end of the bar 38 and the cam 39 is a block 40, Fig. 2, shown as pivoted on the bar 38. This block is connected by a link 41 to a pneumatic 42. A spring 43 normally holds the block 40 out of the path 15 of the cam 39 and also holds the pneumatic 42 in distended condition. The pneumatic 42 is connected by a passage 44 to a valve-chamber 45, in which is a well-known diaphragm-valve 46, which is connected by a 20 flexible tube 47 to one of the ducts 13 in the tracker 12, in which suction is maintained. The plunger 36 may be provided with springs 48 (shown in Fig. 4) to cushion the blow delivered thereby. Located transversely of 25 the frame 1 and in the present instance forward of the container and plunger already described are transverse guide-bars 49 and 51, through which pass a plurality of rods 50, shown as twenty-nine in number, the lower 30 end of each of which forms a printing device, adapted in the present instance to produce a round dot on the sheet to be marked. Each of the rods 50 is normally held upward out of operative position by a light spring 52 and is 35 acted on by a finger 53 on a pneumatic 54, Fig. 2. The pneumatics 54 are shown as extending alternately to the front and rear of the machine to economize space. Each of the pneumatics 54 is connected by a passage 40 55 to a valve-chamber 56, in which is a double valve 57, adapted to connect the passage 55 and pneumatic 54 alternately with atmosphere or with a suction-chamber 58. The valve 57 is actuated by a diaphragm 59, connected by a passage 60 and flexible tube 61 45 to one of the ducts 13 in the tracker 12.

I have shown in Fig. 2 of the drawings a bleed-hole 62 for equalizing the tension or pressure between the passage 60 and the 50 valve-chamber 56. Bleed-holes of this sort are well-known in the art; but in the present case I have provided for a delicate adjustment of the volume of air passing therethrough by placing in the wall of the chamber 56 an aperture closed by a screw 63, which can be adjusted to partially close the bleed-hole 62 as desired.

The operation of the device so far described is as follows: A master-sheet 64, previously wound on a roll 65, (see Fig. 5), is passed over the ducts 13 in the tracker 12 and between the rolls 9 and 10, by which it may be moved forward step by step in unison with a sheet 66 to be marked. The sheet 66 may 65 be wound on the shaft 2 (see Fig. 2) and passes

between the rolls 3 and 4. Power being applied to the main shaft 19, the two sheets 64 and 66 are fed forward step by step between their respective rolls. Carbon-ribbons are wound on the drums 22^x and 23^x, passed over the sheet 66, and engage with the drums 22 and 23, respectively. These are fed as used by means of the wheel 24, dog 25, lever 26, and cam 27, already described. The master-sheet 64 (see Fig. 6) is provided near one of its edges with two linear series of perforations 67 and 68, which are caused to pass over the particular ducts 13 connected, by means of the tubes 341 and 47, to the pneumatics 34 and 42, respectively. The passage of one of the apertures 67 over its duct 13 acts in the well-known manner to collapse the pneumatic 34, the ducts 13 in the tracker 12 being connected with a source of air suction. (Not shown.) The collapse of the pneumatic 34 acts, through the link 33 and lever 32, to force the plunger 31 through the aperture 30 at the foot of the container 29. The container 29 has first been fed with a plurality of slugs 69, on the lower faces of which are formed type letters "FF," "F," "P," "PP," and the like. These are of course placed in the container in the order in which it is desired they shall appear on the sheet 66 to be marked. The movement of the plunger 31 acts to force one of the slugs 69 into operative position under the vertically-reciprocating plunger 36 and above the path of the sheet 66 and carbon-ribbon 66^x. The passage of a succeeding aperture 68 in the master-sheet 64 acts, through the tube 47, to raise the valve 46 and admit suction to the pneumatic 42, by which the same is collapsed. This acts to draw the block 40 into operative position, so that at the next contact of the cam 39 therewith, caused by the rotation of the shaft 19, the lever 38 and plunger 36 will be forced downward, thereby printing the particular character on the slug through a superposed carbon-sheet on the music-sheet 66 in the desired position. The master-sheet 64 is also provided with a series of apertures 70, arranged to form an irregular broken line adapted to indicate the expression to be given the rendition of the music or for any other desired purpose. These apertures 70 pass over the ducts 13 in the tracker 12, which are connected by the tubes 61 to the several pneumatics 54, it being of course understood that the number of tubes 67 and ducts 13 connected therewith is equal to that of the pneumatics 54, in the present instance twenty-nine, so that the passage of the perforations 70 in the master-sheet 64 over the respective ducts in the tracker acts to depress the pneumatics 54 in the desired sequence. Each pneumatic 54 acts, through its finger 53, to depress the corresponding rod 50, the lower end of which acts, through the transverse ribbon 66^x, to print upon the music-sheet 66 a dot, so that the

series of perforations 70 on the master-sheet 64, (shown in Fig. 6 of the drawings,) will effect the printing of the similar series of dots 71 on the music-sheet 66. (Shown in Fig. 7.) In practice the step-by-step movement given to the sheets 64 and 66 is about one-sixteenth of an inch at each step, and the rods 50 are in practice approximately three-eighths of an inch apart, so that the line of dots 71 on the sheet 66 will be substantially as represented in the drawings.

The operation so far described refers to the printing of the letters or characters and of the line of dots on a single music-sheet. It is, however, desirable to print a number of music-sheets at the same time, and for this purpose a plurality of carbon ribbons 66^x (not shown) are wound upon the drums 22^x 23^x and the end of each passed above one of the sheets 66 and secured to the drums 22 and 23 on the opposite side of the machine. It is obvious that in this manner each of the sheets will be properly printed in the manner above described, the process being similar to that of the manifolding-work done on an ordinary type-writer.

The modified form of the device (shown in Figs. 8 to 16 of the drawings) is intended to provide means for the simultaneous marking of a still greater number of the music-sheets. Except as specified, the construction and operation of the machine may be similar to that already described. Means are provided for separating the sheets 66 to be marked into groups lying one above the other, each of the sheets having its superposed carbon-ribbon 66^x. Between the groups are placed relay-slugs by which the printing on the lower groups of sheets is performed. For the printing of the letters and similar characters at the edge of the sheet a plurality of horizontally-disposed containers 72 is provided, one above the other, each of which, as shown in Fig. 8, extends rearwardly from the machine. In these are placed the slugs 69, the sequence of the slugs in each container being, of course, arranged as in the form of the device already described. Springs 73 act to feed the slugs 69 in sequence to their forward position, where they lie in the respective paths of horizontally-disposed plungers 74, Fig. 9, the free ends of which are pivoted to a vertical bar 75, in turn pivoted to a lever 76, which is connected to the pneumatic 34 in the manner and for operation as already described. As shown in Fig. 14, the parts 74, 75, and 76 are bifurcate for the passage therebetween of the carbon-ribbons 66^x. The plungers 74 act to move the slugs 69 through passages formed between transverse walls 77. The first movement of the slugs in such passage acts to bring them in the path of the vertical plunger 36. The blow given the upper slug 69 by the plunger 36 is transmitted through the groups of music and car-

bon sheets to each of the similar slugs below, so that all the music-sheets are simultaneously printed. To retain each slug 69 in correct position beneath the plunger 36 until it has been operated upon thereby and afterward to permit it to move out through the passages formed by the walls 77, each of these latter is provided with a spring-catch 78, having its forward end 79 projecting inwardly into the passage, so as to engage the slug therein. (See Figs. 9 and 14.) On the catch 78 is a stud 80, the head 81 of which rides in a groove 82 in a bar 83. Each of the bars 83 is secured to one of the plungers 74, so as to move therewith exterior of the wall 77. On the bar 83 is a cam-surface 84, on which the stud-head 81 rides when the bar is retracted after its feeding movement. This raises the end 79 of the catch 78 out of the path of the slug 69, so that the latter is free to move. The succeeding forward movement of the plunger 74 and of the bar 83 again permits the return of the device to the slug-engaging position shown in Fig. 14.

In Figs. 11, 12, and 13 I have shown the device modified for the simultaneous printing of a plurality of groups of sheets as applied to the printing of the line of dots 71. A cross-beam 85 is built up to provide a vertical series of passages 86 for the longitudinal moving of the music-sheet 66 and a like series of intersecting transverse passages 87 for the carbon-sheets 66^x. Beneath and in vertical alignment with each of the rods 50 each of the partitions 88, separating the passages 86 and 87, is pierced by an aperture 89, the upper end 90 of which is enlarged, as shown in Figs. 12 and 13. Resting on each of these apertures is a slug 91, consisting of a body portion 92, having sliding movement in the portion 90 of the aperture 89, and of a depending portion 93, passing through the lower part of the aperture 89. As plainly shown in the drawings, the body 92 of the slug is of less depth than the recess 90, so that the slug is capable of vertical movement through the aperture to print on each of a group of sheets beneath a dot similar to that made by the end of a rod 50.

It is obvious that the second form of the device described differs from the first form only in the reinforcing-slugs, by which several groups of superposed music-sheets and carbon-ribbons may be simultaneously printed, so that a greater number of music-sheets may be marked at a single passage of the master-sheet over the tracker 12.

It is clear that many modifications other than those shown may be made in my device without departing from the spirit of the invention.

By the term "ribbon" I mean, of course, to include ribbons and sheets of widely-varying dimensions carrying ink, carbon, or other printing medium.

What I claim is—

1. In a machine for marking music-sheets, means for feeding forward a perforated master-sheet, means for feeding forward a sheet to be marked, means for securing an exactly commensurate or proportional feeding of the two sheets, a pneumatic tracker coöperating with the master-sheet, a set of printing means for printing at a series of different points on the sheet to be marked, pneumatic ducts leading from the said tracker and pneumatic actuating mechanism for the respective printing means controlled by the said tracker-ducts. 50
2. In a machine for marking music-sheets, 15 a pair of rolls for feeding forward a perforated master-sheet, a second pair of rolls for feeding forward a sheet to be marked, means for securing the coöperative rotation of both pairs of rolls, a plurality of printing means for printing at a plurality of points differently placed transversely of the sheet, means for carrying a printing medium in coöperative relation to said printing means, a tracker over which the said master-sheet operates, 20 and means controlled by the said tracker and master-sheet for actuating the respective printing means. 25
3. In a machine for marking music-sheets, 30 a pair of rolls for feeding forward a perforated master-sheet, a second pair of rolls for feeding forward a sheet to be marked, means for securing the coöperative rotation of both pairs of rolls, a plurality of printing means for printing at a plurality of points differently placed transversely of the sheet, means for carrying a printing medium in coöperative relation to said printing means, a tracker over which the said master-sheet operates, 35 pneumatic tracker-ducts leading therefrom, and pneumatically-actuated means for the respective printing means connected with and controlled by the said tracker-ducts. 40
4. In a machine for simultaneously marking a plurality of music-sheets, a pair of rolls for feeding forward a perforated master-sheet, a second pair of rolls for feeding forward the sheets to be marked, means for securing the simultaneous rotation of both said pairs of rolls, printing means for the last-named sheets, and means for maintaining a carbon-ribbon between such sheets and beneath said printing means. 45
5. In a machine for simultaneously marking a plurality of music-sheets, a pair of rolls for feeding forward a master-sheet, a second pair of rolls for feeding forward the sheets to be marked, means for securing the simultaneous rotation of both said pairs of rolls, printing means for the last-named sheets, and 55 means for moving a carbon-ribbon between such sheets transversely thereof and beneath said printing means. 60
6. In a machine for marking music-sheets and in combination with means for feeding a perforated master-sheet and a sheet to be
- marked, a ribbon or sheet carrying a printing medium and means for holding same adjacent to the sheet to be printed, a series of printing means for printing at different points transversely of the sheet, and means controlled by the master-sheet for actuating the several printing means. 70
7. In a machine for marking music-sheets, 75 a pair of rolls for feeding forward a master-sheet, a second pair of rolls for feeding forward a sheet to be marked, means for securing the simultaneous rotation of both said pairs of rolls, a plurality of independent printing parts, a container for said parts having a discharge-opening therefor, means for moving such parts successively from said container to an operative position, and means for forcing each of such parts when so moved toward the sheet for marking it. 80
8. In a machine for marking music-sheets, 85 a pair of rolls for feeding forward a master-sheet, a second pair of rolls for feeding forward a sheet to be marked, means for securing the simultaneous rotation of both said pairs of rolls, a plurality of independent printing parts, a container for said parts having a discharge-opening therefor, means for moving such parts successively from said container to an operative position, and means independent of said moving means for 90 forcing each of such parts when so moved toward the sheet for marking it. 95
9. In a machine for marking music-sheets, 100 means for simultaneously feeding forward a master-sheet and a sheet to be marked, a container for a plurality of printing parts, means for moving such parts successively from said container to an operative position, and means for forcing each of such parts when so moved toward the sheet for marking it. 105
10. In a machine for marking music-sheets, 110 means for simultaneously feeding forward a master-sheet and a sheet to be marked, a container for a plurality of printing parts, means operated by the master-sheet for moving such parts successively from said container to an operative position, and means for forcing each of such parts when so moved toward the sheet for marking it. 115
11. In a machine for marking music-sheets, 120 means for simultaneously feeding forward a master-sheet and a sheet to be marked, a container for a plurality of printing parts, means for moving such parts successively from said container to an operative position, and means for forcing each of such parts when so moved toward the sheet for marking it, said moving means and said forcing means being each independently controlled by the master-sheet. 125
12. In a machine for marking music-sheets, 130 means for simultaneously feeding forward a master-sheet provided with a plurality of longitudinal series of perforations and a sheet to be marked, a tracker over which said master-

sheet is fed, means for containing a plurality of printing parts, means for moving such parts successively from said container to an operative position, means for forcing each of such parts when so moved toward the sheet for marking it, and pneumatic connections leading from said tracker, whereby said moving means and said forcing means are controlled by independent series of perforations in the master-sheet.

13. In a machine for marking music-sheets, means for simultaneously feeding forward a master-sheet and a plurality of sheets to be marked, a plurality of printing parts, at least one of which is interposed between said last-named sheets, and means for simultaneously forcing each of said parts toward the sheet on which it is imposed.

14. In a machine for marking music-sheets, means for simultaneously feeding forward a master-sheet and a plurality of sheets to be marked, containers for sets of movable printing parts, means for moving such parts from said containers so that at least one of such parts is interposed between said last-named sheets, and means for simultaneously feeding a part from each of such sets toward the sheet on which it is imposed.

15. In a machine for marking music-sheets, the combination of means for supporting and feeding a master-sheet, means for supporting and feeding a sheet to be marked, a series of printing devices arranged transversely of the sheet, a ribbon or carrier for the printing medium supported transversely of the sheet, and actuating means controlled by the master-sheet for severally actuating and controlling the series of printing devices.

16. In a machine for marking music-sheets, means for supporting and feeding a master-sheet, means for supporting and feeding a plurality of superposed sheets to be marked, a plurality of ribbons carrying a printing medium and interposed between the respective sheets to be marked, means for supporting and holding the said ribbons independently of the sheet-carrying means, and a series of printing mechanisms controlled from the said master-sheet and disposed to print at different points transversely of the said sheets to be marked.

17. In a machine for marking music-sheets, means for supporting and feeding a master-sheet, means for supporting and feeding a plurality of superposed sheets to be marked,

a plurality of ribbons carrying a printing medium and interposed between the respective sheets to be marked, means for supporting and holding the said ribbons independently of the sheet-carrying means, and means for feeding the said ribbons transversely to the feed of the sheets to be marked, and printing mechanisms controlled from the said master-sheet.

18. In a machine for marking music-sheets, means for supporting and feeding a master-sheet, means for supporting and feeding a plurality of superposed sheets to be marked, a plurality of ribbons carrying a printing medium and interposed between the respective sheets to be marked, means for supporting and holding the said ribbons independently of the sheet-carrying means, means for feeding the said ribbons transversely of the feed of the sheets to be marked, and a plurality of separately-controlled printing mechanisms arranged to print at a plurality of different points transversely of the sheet and in line with the said ribbons, and means for controlling the printing mechanisms from the said master-sheet.

19. In a machine for simultaneously marking a plurality of music-sheets, a pair of rolls for feeding forward a master-sheet, a second pair of rolls for feeding forward the sheets to be marked, means for securing the simultaneous rotation of both said pairs of rolls, a series of printing means for the last-named sheets and disposed transversely thereof, and means for maintaining a carbon-ribbon between such sheets and beneath said printing means.

20. In a machine for marking music-sheets, means for simultaneously feeding forward a perforated master-sheet and a sheet to be marked, a tracker over which said master-sheet is fed, a series of rods disposed above said second-named sheet and transversely thereof, printing means at the lower ends of said rods, a series of pneumatics, one for each of said rods for forcing them down toward the sheet, and pneumatic connections from said tracker to said pneumatics.

In testimony whereof I have signed this specification in the presence of two subscribing witnesses.

PHILIP JACOB MEAHL.
